UNITED STATES PATENT OFFICE

2,225,473

RAILWAY SIGNALING SYSTEM

John Balmain Griffiths, London, England, assignor to International Standard Electric Corporation, New York, N. Y.

Application August 9, 1938, Serial No. 223,838
In Great Britain August 10, 1937

6 Claims. (Cl. 246—134)

This invention relates to remote control of railway signal and track systems.

Many cases arise in practice of a set of siding track or switch points and signals, for instance, which are changed at infrequent intervals but for which a signal box is provided, the majority of the signalman's work being to act as a tandem repeater for messages between busy signal boxes on either side.

10 Considerable economies could be achieved in systems mainly provided with local control, if control of infrequently operated switch points and signals were placed in the hands of adjacent main signal boxes, and it is the main object of the invention to provide such facilities.

15 The main feature of the invention comprises a system for the remote control of railway signals and switch points comprising route setting equipment which is located adjacent the track equipment to be controlled which is of the kind normally directly responsive to the manual operation of route levers, keys or the like to control the setting of signals and switch points in accordance with the route to be set up and which incorporates electrical interlocking between routes, control panel equipment at a distant switch point comprising route levers, keys or the like the movements of which are not interlocked with one another in any way, a signal channel between the 20 route setting equipment position and the distant switch point together with signal transmitting equipment at the distant switch point controlled by the levers, keys or the like and signal receiving equipment at the route setting equipment position arranged to be capable of setting up a unique condition corresponding to every route setting lever or like operation possible at the distant switch point whereby said signal receiving equipment is adapted to simulate panel equipment for 25 control of the route setting equipment.

It is proposed to use control signals for instance, of the constant total code type, each characteristic of a complete set of conditions to be set up at a remotely controlled set of signals and points.

30 45 The proper reception of a constant total code signal—correct number of digits and correct total number of impulses—checks that no error has occurred in transmission.

The new set of conditions would be set up in 40 response to a correctly received code and a simple signal would be sent back to inform the signalman that the code sent had been correctly received.

45 Preferably the route signal would be used to set a sequence or other switch controlling the signal

and points circuits in the manner described in the copending application of J. B. Griffiths and A. Brown, Serial No. 209,198, filed May 21, 1938.

An answering constant-total code signal could be returned to the control cabin on correct receipt of a setting signal, said answering signal being individual to the particular setting signal received. In this case, the setting up of the route at the controlled position would not take place until the signalman, on receipt of the check code 10 signal, sent an operating signal.

This system may be used in conjunction with a centralized traffic indicator system such as that described in British Patent specification No. 461,136, accepted February 10, 1937 which is arranged to test the position of all equipment on a length of track at frequent intervals and to change the setting of an indicator at the control cabin accordingly. The change in the setting of the signals and switch points in response to a 20 constant-total code setting signal would be indicated in a short time on the indicator board.

This system of remote control and indication, besides being applicable to the circumstances detailed above, is also capable of use for the remote 25 control of a number of spaced sets of switch points and signals in tandem, for instance, by using a preliminary constant-total code signal characteristic of the set to be controlled.

The invention will be clearly understood from 30 the following description of one embodiment thereof shown in the accompanying drawings, in which:

Fig. 1 shows schematically the equipment layout from the remote control and indication of a 35 change-over set of switch points and signals;

Figs. 2A and 2B taken together show the code transmission equipment at a signal cabin for remote control;

Figs. 2C and 2D show the code receiving equipment adjacent the set of switch points and signals to be remotely controlled for use with the transmitter of Figs. 2A and 2B;

Figs. 3A and 3B show the centralized traffic indicating equipment at the signal cabin; while 45

Figs. 3C and 3D show isolated and group way station equipments of the centralized traffic indicating system.

Fig. 1 shows a general diagram of the arrangement, illustrating at PSG the track layout for a 50 small interlocking area which is required to be controlled from a panel CPE in a remote signal cabin SC.

The control panel CPE incorporates a mimic diagram of the track with route switches situated 55

at points in the diagram corresponding to the signals, individual point switches provided for the emergency control of the switch points, switch point detection indicators and track circuit indicators as described in the copending application of J. B. Griffiths and Andrew Brown, Serial No. 209,198.

The control switches on the panel are not interlocked in any way and are free to move at any time. The operation of any control switch starts up code signal transmitting equipment STE which transmits a unique code (constant total, that is, one in which the sum of the digits transmitted for any code is constant, is preferred) to a code signal receiving equipment SRE adjacent the points and signals to be controlled.

The receipt of this code will actuate sequence switch interlocking route setting equipment RSE to complete the desired control, provided that it is safe to do so in respect of the routes already set up and local traffic conditions.

The sequence switch interlocking equipment RSE will be similar to that already described in Application Ser. No. 209,198 and route relays operated by the code receiver correspond to the panel route switches operated by the signalman.

Having effected the necessary switching by remote control, in conjunction with local interlocking, it is still desirable to provide the signal man with a complete indication of the state of his track and traffic and it is proposed to accomplish this over a separate communication channel by means of a centralized traffic indication system similar to that described in British Patent No. 35 461,136.

For the purposes of this description it is assumed that the track between the signal cabin and track section PSG is controlled by automatic signaling, in which case it is only necessary to 40 indicate to the signal man the occupation of the various track sections thereof, a way-station WS being installed adjacent to each track section.

In the case of section PSG it is necessary to indicate the conditions of signals, switch points 45 and track sections, and since all the equipment relative to these signals, points and track sections, is mounted at one location, it is unnecessary to provide completely separate way-station units for each device to be indicated, and considerable economy is effected by providing a group way station GWS for this equipment. The way stations are connected by a signal channel to indicator equipment IE in the signal cabin SC.

A more complete understanding of the system 55 may be had by consideration of the wiring diagram of the circuits of CPE, STE, SRE and RSE shown in detail in Figs. 2A, 2B, 2C and 2D, these figures being arranged in a line with their vertical dimensions adjacent each other. In these 60 diagrams the relays are shown in solid lines and the contacts are not all shown directly adjacent the controlling relays because of the complexity of the circuit. To facilitate understanding, the relays are shown in light dotted lines adjacent 65 each of the contacts which they control.

The cams of the sequence switches are shown by the usual convention, those associated with switch S being designated SA, SB, SC, etc., and those associated with switch T being designated 70 TA, TB, TC, etc. Switches S and T are of well known construction and are indicated only by the conventional schematic illustration of sequence switches. The brushes making continuous permanent contact with the cams are shown 75 directly connected thereto, those contacting only

at discreet positions are designated by numerals 1, 2, 3, 4, etc., see cam SG, Fig. 2A, those making continuous contact between certain positions being designated $\frac{1}{2}$, see cam SP, Fig. 2B, and those making contact at every position but not continuous therebetween being designated 1-18, see cam SA, Fig. 2B. The designation e. g. $1\frac{1}{4}/2$ cam SB, Fig. 2A, indicates that contact is made at position $1\frac{1}{4}$, just a little in advance of position 2, so that the switch may be brought to a stop in position 2. The usual positioning cam on the sequence switch serving to properly center the contacts.

The panel equipment CPE is provided with a manual key for each route, 21 R.K.—30 R.K., Fig. 15 2A, each key having normal and reverse positions, and a channel key for each track point each having normal, neutral and reverse positions and each indicated, e. g. by 61 P.K.N. and 61 P.K.R., Fig. 2A.

To set up a route one of the signal keys is operated and starts a searcher-switch into operation to test the proposed route setting. This switch then stops in its chosen setting a further code switching arrangement is energized and transmits from STE signal impulses corresponding to the signal or switch point setting desired.

This code is received at the signal receiver SRE at which point is provided means responsive to the code sent. If the code is properly received a circuit is completed for transmitting back to the sending end a check signal to this effect, and then operate the route setting equipment to set up the chosen route.

If the code is not properly received a signal 35 indicating the error is transmitted back to the control panel. The operator may then try again to set up the route if desired after operating a fault clearing switch to clear faults which may exist in the circuit.

In order that conflicting routes may not be set up the transmitter is provided with a set of sequence switches and interlock circuits so that code signals will not be sent to the receiver unless the track is clear. By sending a route breakdown signal the routes previously set up may be reset to the original condition when desired.

As a further check on the operation of the system an arrangement is provided operated by the switch points and signals for indicating at 50 the signal cabin on equipment IE the condition of the tracks and signals.

At the signal cabin is provided a distributor arrangement continuously driven by a motor or some other means. This distributor sends out positive or negative impulses which pass successively through any stations in the track circuit, such as way stations WS and group way stations GWS. The number of impulses from the distributor correspond to the stations to be checked. Upon receipt of the signal, for example at the first way station, an indication of clear or occupied, is given depending on the condition of the corresponding track section at the time. At 65 the way station relays are arranged to complete a circuit through to the next station so that the succeeding impulse is received at the next station and so on through the entire track system under control of the signal cabin. In dependence on 70 the condition of the track sections as indicated, signal lamps are lighted at the equipment IE so that the signalman is continuously apprised of the track condition. A complete description of the operation follows considering particularly ex- 75

amples of route setting signals and operation of the system.

Consider the case of a signalman attempting to set up route No. 21, by operating key 21RK.

- 5 The signalman operates the panel control switch 21RK to its "reverse" (lower) position, thereby completing a circuit from positive, contacts 21RK, 21rl, resistance 21YA, winding of relay SS to negative operating relay SS.
- 10 Operation of SS energizes the searcher switch clutch magnet SM (Fig. 2B) from positive, contacts st3, ss1, cam TC (when the transmitting switch T is in its home position), clutch magnet SM, relay MS to negative operating SM and MS.
- 15 Contacts ms1 and ms2 closed by MS start up the common motor M for all sequence switch drives from a current source AC and the searcher switch S will rotate as long as the above circuit persists. Wherever the searcher switch started 20 it revolves into position 1, whereupon a circuit is completed for the relay ST (Fig. 2A) from positive, contacts 21RK, 21rl, cam SB in position 1, winding of relay ST to negative, causing ST to operate and close its contacts.
- 25 The contacts st3 (Fig. 2B) interrupt the circuit for the searcher switch clutch magnet SM, thus stopping the searcher switch in position 1, corresponding to the panel switch 21RK just operated. Relay ST remains locked over contacts st1 (Fig. 2A) and cam TD (Fig. 2D) until the switch S completes a revolution.
- The clutch magnet TM of the transmitting switch T is then energized from positive, contacts st3, cam TB in position 1, clutch magnet TM and 35 relay MS to negative operating TM and MS.
- The transmitting switch T then drives under control of its TA cam, which forms a holding circuit for clutch magnet TM after cam TB leaves position 1, until it reaches position 15½. During 40 this revolution of the transmitting switch, contacts is1 send a code of impulses over the line L1, L2, the relay IS being operated from positive, contacts st2, the impulsive cam TQ in conjunction with cams TH—TP and certain coding contacts a—q. In this case the contacts b and k are connected to positive via contacts st2, cam 45 SP with the searcher switch S in position 1, and contacts 21rl3. As the transmitting switch revolves, relay IS is operated for a long "prepare" 50 period from TQ, released for two impulses by the impulsive cam TQ, then held operated between positions 3¾/5¾ for a long interdigital pause by contacts b on cam TH, released for four more impulses from the impulsive cam TQ, held operated 55 for a second interdigital pause by contacts k on cam TM between positions 8¼/10¼ and released for a third digit of seven impulses and finally held operated over cam TP, to which positive is applied in position 14¼/18.
- 60 It will be seen, therefore, that the code 241 is transmitted while the transmitting switch T moves into position 15½.

Relay FPR is then operated from positive, cam TD winding of FPR to negative and the contacts 65 fpr1, fpr2 transfer the line wires L1, L2 to the operating coil of relay RC. In order to guard against the possibility of false operation due to code faults, the codes chosen are so arranged that each code consists of three digits adding up to a constant total (13 in this case).

Relay IR, at the receiver, Fig. 2C, operates in response to battery feed from the transmitter circuit energizing RG from positive over ig1 and operation of RG operates RGA over contact rg1.

70 Relays RG and RGA are held operated through

the entire code. Relay DC is pre-energized from positive, rg1, ca1 to negative at the beginning of each digit, and after CA operates during each digit, as explained later, DC is held by repeat impulses from contacts IR1 via dca1, ca1. DC 5 operates DCA from positive contacts dcl winding of DCA to negative.

During the first digit, DMA is operated from positive rg1, dca2, hdx1 winding of DMA to negative, and locks via dma2. Operation of DMA 10 closes a circuit for DMB at dma1 operating DMB. During the second digit DMC and DMD operate, and during the third digit, DME and DMF as will be described in detail later.

Operation of relay PO closes an energizing circuit for relay POA via ir1, dca1, po1, po1, po2, cb1 to negative. Operation of relay POA moves its contact poal over preparing a circuit for relay PE. At the end of the impulse PO remains operated in series with POA from positive, rg1, 20 dma4, winding of POA, po1, pe2, winding of PO to negative.

The second impulse is then routed from positive, ir1, dca1, poal winding of relay PE to negative, operating PE and releasing PO and POA 25 at pe2. Relay PE locks over its contact pe1, and release of relay POA returns its contact poal to its original position.

It will be seen, therefore, that relay PO is operated by the first impulse, released by the second, re-operated by the third and so on.

The number of operations of relay PO is counted by the train of counting relays CA—CG.

Positive, rg1, dma4, po2, cb1, winding of CA operates CA for the first impulse closing a circuit 35 through winding of relay CB at ea2. Relay CB does not operate, however, since its winding is short circuited at po2. The opening of po2 on the second impulse allows CB to operate in the locking circuit of CA. Similarly the third to the 40 seventh impulses operate CC . . . CG. At the end of the first digit relays DC and DCA release. The last operated counting relay, in the example selected relay CB, in conjunction with relays DMA and DMB, selects a relay in the 100 storage 45 group, HDA, HDG, i. e. HDB which operates via rg1, dca2, ir2, cg3, cf2, ce3, cd2, cc3, cb2, dmb2 to negative, and locks at hdb1, in series with HDX to rrg1.

Operation of HDX, releases DMA at hdx1 50 which in turn releases the operated counting relays CA. Thereafter relay DC is re-operated in readiness for the second digit. Due to the operation of HDX, DMC and DMD are operated instead of DMA, DMB over rg1, dca2, hdx1, 55 dma3, tnx1 and dma1, respectively. The second digit is received and stored in a manner similar to the hundreds digit on one of the tens relays, TNA, TNG, in the example TND, which locks at tnd1 in series with TNX. For the third digit 60 DME, DMF are energized since TNX transfers the circuit to relay DME similarly to the transfer after the hundreds digit and remain energized after the digit is received, the third digit being stored on the counting relays themselves. 65

When relay DC is released at the end of the third digit, one outlet from the receiver is marked, according to the combination of hundreds, tens and counting relays then operated. If the code 241, for instance, has been received, 70 then the second hundreds relay HDB, the fourth tens relay TND and the seventh counting relay CG, would all be operated together with the third digit mark relays DME and DMF.

It will be seen that a circuit is then provided 75

for the receiving relay 21 DLR connected to the terminal 247 over *rga1, ir2, cg3, dmc5, hdb2, tnd2* winding of 21 DLR to negative. In order not to as are used in the particular example are shown 5 in Fig. 2D. Thus only connection to lines corresponding to code numbers 247, 517, 526 and complicate the circuit unduly only such relays 10 535 are shown. It is clear that similar connections are to be made to the other lines for completion of the system.

The contacts of the storage and counting relays are grouped in such a way that no outlet at 15 all is provided unless the three digits total 13. If the correct code is received and an outlet relay 20 operated, then on the release of relay IR at the end of the code, the winding of relay OK is introduced in series with the selected receiving relay, *rga1, dca2*, and the rest of the circuit as previously traced and the relay OK consequently operated. This relay sends the check-back impulse 25 to the transmitter circuit, Figs. 2A and 2B, by connecting battery feed via *ok1, ok2* to line *L1, L2*.

The check back impulse sent back to the transmitting point operates relay RC, Fig. 2B. Relay RC locks via *rc1* and cam TD.

Contacts *rc3* apply to a positive over cam TB in position 15½ to re-energize the transmitting clutch magnet TM in series with MS and so cause 30 the switch T to drive home. At the end of every code transmitted, relay FPR is energized in position 15½ of cam TD and the fault indication lamp FIL will be illuminated over contacts *fpr3* for a short period and in the event of the check 35 back impulse not being received the transmitting switch will remain in position 15½ and the fault indication lamp will remain illuminated.

Assuming that the code has been correctly received, a circuit will be completed from positive, 40 contacts *rc2* (Fig. 2A), cam TE in position 15½, high resistance winding of relay AR, cam SK in position 1, winding of relay 21LR, resistance 21YB to negative.

Relay AR operates on this circuit and locks 45 over contacts *ar1*, cam TF and contacts *rc2*.

The relay 21LR, however, cannot operate in series with the high resistance winding AR, but operates when this winding is short circuited by contacts *ar2* and cam TE.

When relay 21LR operates, it locks over contacts 50 21lr2 in a local circuit with resistance 21YB and thereafter relay 21LR can only be released by short circuit.

When route 21 is set up, key 21RK is in its lower 55 position and relay 21LR is energized, so that the upper contacts 21lr1 are closed. To break down the route, key 21RK is returned to normal position, and transmission of code 256 is initiated starting the motor and operating switches S and T in the same manner as described in connection with the transmission of code 247. When switch T reaches position 15½, relay AR is not operated, since it is short circuited via cam SK and contacts 21lr2. In this case when the transmitting switch moves into position 16½, positive is applied over contacts *rc2*, cam TE, contacts *ar3*, cam SG in position 1, resistance 21YB to short circuit the winding of relay 21LR which would therefore release.

It will be seen, therefore, that when the route 70 setting code is sent relay 21LW will be operated at the end of the code and conversely when the route breakdown code is sent, relay 21LR will be released by short circuit at the end of the code.

When relay 21LR was operated after transmit-

ting the route-setting code 247, the operation of contacts 21lr1 released SS and ST and at the same time prepared a circuit for the reoperation of SS as soon as the switch 21RK was restored to normal. 5

When the switch 21RK is restored to normal, the cycle of operations just described in connection with operation of the key will be repeated, except that the code transmitted will be 256 since the contact of cam TM will be marked instead of 10 contact *k* of cam TM, over contacts 21lr3. Setting up of connections through code 256 short circuits the winding of relay 21DLR positive, 15 21dlr1, *tne2, hdb3, dmc6, ef2, eg3, ir2, dca2, rga1*, to positive, causing it to release. 15

It should be noted that the code transmitted and the LR relay operated have been associated with route 21 by virtue of the fact that the searcher switch S was standing in position 1, one position of the searcher switch being allocated 20 to each route.

In addition to the route control switches, the panel is equipped with a number of individual switch point control switches. These switches are capable of taking up one of three positions, normal—which attempts to set the switch points to normal, reverse—which attempts to set the switch points to reverse, and central—which leaves the switch points free to be operated either normal or reverse, as required by the setting of the route 30 switches.

On the transmitter circuit the switch point control switches are shown in two parts, for example, 61PKN, 61PKR. The switches are shown in the central position: if operated to the normal position then the portion 61PKN will be operated and if operated to the reverse then 61PKR will be operated. 35

One position on the searcher switch S is allocated to the normal position of the key and one 40 to the reverse position and, furthermore, NLR and RLR relays are provided associated with the two positions of the control switch.

The method of positioning the searcher switch and transmitting the code is similar to that described for the route switch except for the following points, and therefore need not be traced in detail.

Since it is impossible for a switch point control switch to occupy the normal and reverse positions at the same time because of its construction, the transmission of, say, the normal code, renders it superfluous to transmit in addition a central code in the event of the switch having been operated right over from reverse to normal 55 without stopping in the central position.

Contact 61lr3 is therefore included in the locking circuit for relay 61RLR and contacts 61lr2 in the locking circuit for NLR. Furthermore, the same code (517) can be used to indicate that the switch point control switch is restored to its normal position, independent of whether it was operated from normal (in which case the searcher switch will be in position 11 with relay 61NLR operated) or from reverse (in which case the searcher switch will be in position 12 with relay 61RLR operated). 65

In the event of any fault occurring in the transmission or reception of the code, the check 70 back signal will not arrive and the transmitting switch will remain in position 15½ with the fault lamp illuminated, as explained above in connection with the route setting switch. The signalman must then operate the fault clearing key FK 75

Remote indication of points, signals and tracks

(Fig. 2B) which operates the slow release relays CFG over an obvious circuit. On the release of the fault key, relay CF will be operated over contacts *cfg1* and cam TG in position 15%.

5 Relay CF locks over contact *cf1* and cam TD, and, contacts *cf2* energize the clutch magnet TM, positive, *cf2*, cam TB, magnet TM, relay MS to negative to drive the switch T home.

Since the switch returns home without relay 10 RC operated, no operation or release of the LR relay corresponding to the operated key will be effected.

If the panel key which originated the code has not been restored, then a circuit will still be 15 available for relay ST when the transmitting switch reaches its home position and therefore the transmitting switch will commence a second revolution and re-transmit the same code.

The circuits completed by the outlets from the 20 code receiver are utilized to operate certain route selecting or switch point operating relays. For example, a relay 21DLR will be operated when positive is applied by the code receiver, as explained above, to the terminal 247.

25 When operated, relay 21DLR will lock over a second winding and 21₁dr1 in series with a resistance and from this condition can only be released when a further positive is applied by the code receiver to the terminal 256.

30 It will be seen on reference to the transmitter circuit that the code 247 is transmitted when the panel switch for route 21 is reversed and code 256 is transmitted when the same switch is restored to normal. It is apparent, therefore, that relay 35 21DLR, adjacent the switch points and signal, follows the operation of the corresponding panel switch.

Similarly two switch point control relays 61NDLR and 61RDLR follow the operation of the 40 individual panel switch for controlling switch points 61. The operation of the panel switch 61 to normal will transmit code 526 as explained previously and subsequently operate 61NDLR which locks over 61ndlr1, while the operation of the 45 panel switch to reverse, transmits code 535 and operates relay 61RDLR which locks over 61rdlr1. The code 517 transmitted when the panel switch is restored to its central position either from normal or from reverse, will effectively short circuit the holding windings of both relays 61NDLR and 61RDLR, and when both these relays are de- 50 energized, switch points will be free for operation to set up a route in accordance with the operation of a route panel key.

55 In the event of the switch point control switch being operated from normal to reverse without pausing in the central position, the operation of the reverse switch point control relay 61RDLR disconnects the holding circuit for the relay 60 61NDLR at 61rdlr2 since it is obviously inadmissible that the normal and reverse switch point control relays should be operated at the same time.

Since it has been shown that relays adjacent the 65 switch points and signals repeat the operation of all route and switch point control switches on the panel, the local interlocking necessary between such routes and points may be provided by means of an interlocking system using sequence switches or wiper switches as described in 70 application Ser. No. 209,198. The principles of this type of interlocking are fully described in this application No. 209,198 and therefore no description of the interlocking arrangements is given in this specification.

The system used for indicating back to the control panel the state of switch points, signals and tracks, is similar in principle to that described in British Patent No. 461,136 and preferably uses a signal channel independent of that used for control codes, although it is possible for the channel normally used for indication purposes to be switched over to carry out the control functions if required.

British Patent 461,136 referred primarily, though not exclusively, to centralised indication of the condition of a number of track relays spaced at intervals along the track, the signal 15 channel being fed through all such locations in turn.

In the example now described, it is assumed that there are a number of individual track locations of this type, together with a number of 20 devices concentrated at one point as, for example, in the interlocking area described above.

Figs. 3A and 3B arranged one above the other show the control station equipment at IE Fig. 1, while

Figs. 3C and 3D show a typical isolated way-station WS, GWS of Fig. 1, such as may be used for repeating the condition of a track relay to the control room and also the manner in which the way-station equipment may be modified when a 30 number of functions to be indicated are concentrated at one point and for showing the connection of the circuit should be arranged, in order, to the right of Fig. 3A.

The operation of this circuit is briefly as follows:

At the right hand side of Figs. 3A and 3B is shown a series of typical contacts from one level of a continuously motor driven distributor, the moving arm of which is connected to line LN1. 40 When the moving arm passes over the first contact of the distributor, current is fed from the positive pole of battery MB, line L2, track contacts *tr1*, if the corresponding track section 301/303 is clear, rectifier RA, *oal*, line LN1' at 45 the first track position line LN1, the first wiper contact winding of relay 301/303MR to negative pole of battery MB. If track 301/303 is clear at this instant, the relay 301/303MR will be operated and will lock itself through lock cam 50 CAM C.

When the distributor arm moves on to the second contact, the poles of reverse current from the auxiliary battery AB will be fed over the line. This will pass through rectifier RC and the relay P at the first track location. Relay P operates independently of the condition of the track relay and operates relay O from a small local battery *t*, contact *pt1*, —, closing contact *o1*. Relay OA, however, does not operate as it is short 60 circuited at *pt1*.

When the distributor arm moves off this contact, relay P is released and relay OA thereupon operates in series with relay O, *t*, winding of OA, *o1*, *acal*, winding of O, —. Contacts *oal* transfer line LN1' from track section 301/303 to the succeeding track section 312 where a similar cycle of operations is completed and the relay 312MR in the control station will be operated if the relevant track section is clear.

In the same way MR relays for all the track sections in the automatic territory will be connected successively through contacts of their associated track relays and will operate in each case if the track section is clear.

Line LN1 is then switched through to the composite way-station unit GWS associated with the interlocking area.

The next testing impulse is fed through relay 5 21/22MR at the control station, contacts OA1, rectifier CRA at the way-station, back contacts of all CR relays, contacts 21hr3 and 22hr3 (provided that neither of these signals 21 and 22 has been cleared) and back over line NL2 to the main battery.

10 It will be seen, therefore, that relay 21/22MR operates if the signals 21/22 are at danger.

The next stepping impulse is routed over an obvious circuit through rectifier CRC and relay 15 CP operating CP regardless of the track condition. CP operates relay CO, +, *caca1*, *cpl*, *coa1*, winding of CO, —, relay CP is released and COA operates in series with CO, +, winding COA, *cpe2*, CO1, winding CO, —.

20 It should be noted that all the local switching at the remote station is controlled by a positive fed over contacts *caca1*.

The second operation of CP will cause relay 25 CPE to be operated off contacts *coa1* and contacts *cpe2* thereupon release relays CO and COA. It will be seen, therefore, that relay CO is operated by the first stepping impulse, released by the second, re-operated by the third, and so on.

The first operation of CO causes relay 30 21/22CR to operate t, CO2, back contacts of relay 23/24CR, winding of 21/22CR, —. On the release of CO relay 23/24CR comes up in series with 21/22CR. The next operation of CO causes relay 35 25/26CR to operate and so on through CR relays associated with all the signals, points and track relays in the remote controlled area.

The second testing impulse, which is fed through relay 23/24MR in the control station arrives after the first stepping impulse and is fed 40 through rectifier CRA, back contacts of all CR relays up to 23/24CR and front contacts of 21/22CR through contacts 23/24hr3, provided that the signal 23/24 is at danger.

45 As successive stepping impulses operate the various CR relays, so the testing impulses will be fed first through contacts of the HR relays for all signals, then through contacts of the normal and reverse switch point detection relays for all points, and finally through contacts of all track relays.

50 When the distributor approaches the end of its cycle, a selection of MR relays will have been operated and locked over cam C corresponding to the state of all signals, points and tracks.

55 If every testing impulse from the distributor has been effective in stepping the line from way-station to way-station and thereafter in operating all the CR relays correctly, then when the distributor arrives at the point connected to the 60 relay SYN, the relay 208CR at the remote station should be operated and the relay SCR should not be operated since 208CR short circuits SCR. In this condition a synchronising battery situated at the remote station will be connected 65 from the rectifier CRA to operate the relay SYN.

If an insufficient number of impulses have been effective, then relay 208CR will not be operated so the circuit will not be established. Alternatively if too many stepping impulses have been 70 received, then relay SCR will also be operated, breaking the circuit for SYN, so that the operation of the relay SYN is a definite proof that all the way-station equipment has correctly responded to the stepping impulses. This means that the 75 group of MR relays which has been operated can

be accepted as a reliable indication of the state of all signals, point and track relays.

When relay SYN is operated it also locks to CAM C and thereafter cam CAM A is operated by the distributor, so that the setting of the MR 5 relays is transferred to a corresponding group of DR relays over CAM A, *syn2*, the various *mr* contacts and windings of the DR relays, the operated DR relays locking themselves over their front contacts and cam CAM B.

10 CAM D thereupon opens its contacts, breaking the locking circuit for any DR relays which were operated previously and are not required to be re-operated.

CAM B then recloses to restore the locking circuit for the new set of DR relays and thereafter CAM A re-opens. CAM C is then opened to unlock all MR relays, leaving them ready for re-operation in the succeeding cycle.

CAM D then connects the main battery between lines LN2 and LN3, thereby operating the ACA relay at the first track location. ACA unlocks O and OA at *caca1* and the release of relay O transfers at O2 the clearing impulse to the second track location where another ACA relay 25 will be operated. In this way ACA relays at all stations are operated in turn, restoring the way-station equipment to normal. In the case of the remote controlled station the relay CACA is operated, removing the main positive to all counting 30 relays etc., so that they are all released in readiness for the next cycle.

The DR relays at the control station control the illumination of all signal indication, point detection and track indication lamps on the control panel at their *dr2* contacts so that at the end of every cycle of the distributor the complete indication as shown by the control panel, is brought into line with the remote equipment.

As shown, the track indication relays operated 40 for track sections at each way-station control twin lamps 301/303TKE . . . 302TR which are illuminated when the track is occupied, i. e. when the DR relay is de-energized. A positive proof that a track section is clear is required to operate 45 relay DR and extinguish the indication lamps. In the case of signal indications lamps 21/22DKE, 21/22RKE . . . 29/30DKE, 29/30RKE corresponding to the positions of keys 21RK . . . 30RK of Fig. 2A, a green lamp is illuminated 50 when the relay DR is de-energised and it is necessary to receive a positive signal before the relay will be operated, to show that the signal has been placed at danger.

In the case of the point detection indicators, 55 separate relays are provided, for instance, 61NDR and 61RDR, etc. corresponding to 61PKN, 61PKR, etc. Fig. 2A, each relay controlling, for example, two lamps 61NKE, 61RKE, etc., one at each end of the point switch on the diagram. In the event 60 of points being in an intermediate position, no point detection would be indicated.

In the remote indication system described above, a three-wire channel throughout the way-stations has been assumed, the third wire being 65 used as described for clearing down way-station equipment after a test.

It will be clear, however, that the alternative two-wire methods, as described in British Patent No. 461,136 are equally applicable.

70 It is possible that the remote control of a sequence switch interlocking system could be effected by various coding methods other than that described above, and, furthermore, that the indication back to the control panel could be 75

carried out by several known methods as, for example, a coding system in which any change in way-station apparatus originates a unique code which is transmitted back to the control station, 5 where it actuates a receiver to make the necessary change to the control diagram.

The remote indication cycle is continuously repeated so that there is a constantly repeated check of the condition or position of every device 10 which is being supervised.

What is claimed is:

1. A system for remote control of railway signals and switch points, for setting up a selected route over a given track layout by operation of 15 track switches and signals, comprising control panel equipment at a distant point from said signals and switch points comprising independently operable manually adjustable route selecting means, route setting equipment normally responsive to operation of said route selecting means located adjacent said track layout to control the setting of the switches and signals in accordance with a selected route to be set up, said route setting equipment incorporating means 20 providing electrical interlocking between conflicting routes, a transmission channel for transmitting a control signal comprising energy impulses, between said route setting equipment and said control panel equipment at said distant point, signal transmitting equipment at said distant point controlled by adjustment of said independent route selecting equipment for applying control signal impulses to said line corresponding to the selected route, signal receiving equipment at 25 said route setting equipment position responsive to received signal control impulses transmitted over said line, means in said route setting equipment responsive to said received signals for operating said route setting equipment to set up a selected route corresponding to every operation 30 of said independent route selecting means, remote supervisory equipment comprising condition-signaling equipment adjacent the track equipment controlled by said route setting equipment in response to the condition of said signals and switch points, indicating equipment at the 35 distant point arranged to receive via a signal channel indications of the condition of said route setting equipment, and means for providing a continuously repeated cycle of indications of the 40 condition of all the signals and switch points, said remote supervisory equipment also including way-station condition-signaling equipment individual to each track section of a length of 45 track, whereby the indicating equipment at the distant point gives information concerning the condition and setting of a length of track including the said remotely controlled set of signals and switch points.

60 2. A railway signal and points control system as claimed in claim 1 in which said way-stations are arranged first to transmit condition signals to the signal cabin and then to switch through the signal channel to a succeeding way-station, 65 the way-station for said remotely-controlled set of signals and points being arranged to transmit a succession of condition signals giving information of the condition of all the signals and switch points before switching the channel through to 70 succeeding way-stations.

3. A system for the remote control of railway signals and switch points, comprising control equipment at a control station, a plurality of route keys independently operable for initiating 75 transmission of selected route setting signals,

means responsive to operation of a route key for transmitting a selected route setting code signal dependent upon the key operated, receiving means for receiving said code signal responsive to receipt of said code for setting up the selected 5 route corresponding to said received code signal, and means at said receiver for blocking the setting up of said selected route in event it conflicts with another route previously set up.

4. A system according to claim 3, further comprising means at said control station responsive to impulses initiated by blocking of said selected route for indicating this condition, and means for indicating said signal and restoring said receiver to condition for setting up another route. 10 15

5. A system for remote control of railway signals and switch points, for setting up a selected route over a given track layout by operation of track switches and signals, comprising control panel equipment at a distant point from said signals and switch points comprising independently operable manually adjustable route selecting means, route setting equipment normally responsive to operation of said route selecting means located adjacent said track layout to control the 20 setting of switches and signals in accordance with a selected route to be set up, said route setting equipment incorporating means providing electrical interlocking between conflicting routes, a transmission channel for transmitting a control signal comprising energy impulses between said route setting equipment and said control panel equipment at said distant point, signal transmitting equipment at said distant point controlled by adjustment of said independent route selecting 25 equipment for applying control signal impulses to said line corresponding to the selected route, signal receiving equipment at said route setting equipment position responsive to received signal control impulses transmitted over said line, 30 means responsive to said received code signals for operating said route setting equipment to set up a selected route corresponding to every operation of said independent route selecting means, remote supervisory equipment comprising condition-signaling equipment adjacent the track 35 equipment controlled by said route setting equipment in response to the condition of said signals and switch points, indicating equipment at the distant point arranged to receive indications of the 40 conditions of all of said signals and switch points, a signal channel interconnecting said indicating equipment and said condition-signaling equipment, and means for continuously repeating 45 a cycle of said indications from said supervisory 50 equipment to said indicating equipment.

6. A system for remote control of railway signals and switch points, for setting up a selected route over a given track layout by operation of track switches and signals, comprising control panel equipment at a distant point from said signals and switch points comprising independently operable manually adjustable route selecting means, route setting equipment normally responsive to operation of said route selecting means located adjacent said track layout to control the setting of the switches and signals in accordance with a selected route to be set up, said route setting equipment incorporating means providing electrical interlocking between conflicting 60 routes, a transmission channel for transmitting a control signal comprising energy impulses between said route setting equipment and said control panel equipment at said distant point, signal transmitting equipment at said distant point controlled 65 by adjustment of said independent route selecting equipment for applying control signal impulses to said line corresponding to the selected route, signal receiving equipment at said route setting equipment position responsive to received signal control impulses transmitted over said line, means responsive to said received code signals for operating said route setting equipment to set up a selected route corresponding to every operation of said independent route selecting means, remote supervisory equipment comprising condition-signaling equipment adjacent the track equipment controlled by said route setting equipment in response to the condition of said signals and switch points, indicating equipment at the distant point arranged to receive indications of the conditions of all of said signals and switch points, a signal channel interconnecting said indicating equipment and said condition-signaling equipment, and means for continuously repeating a cycle of said indications from said supervisory 70 equipment to said indicating equipment.

75

trolled by adjustment of said independent route selecting equipment for applying control signal impulses to said line corresponding to the selected route, said signal transmitting equipment comprising means for transmitting a plural element code signal, each element comprising a plurality of impulses the total number of impulses being the same for every code signal, signal receiving equipment at said route setting equipment position responsive to received signal control impulses

transmitted over said line, comprising means responsive to reception of all of said code signal impulses to transmit back to the signal transmitting station a signal indicating the correct reception of said code signal, means responsive to correct reception of said received code signals for operating said route setting equipment to set up a selected route corresponding to every operation of said independent route selecting means.

JOHN BALMAIN GRIFFITHS. 10
